DETACHABLE CAP

Howard J. Murphy, Greenwood, Mass., assignor
to United-Carr Fastener Corporation, Cam-
bridge, Mass., a corporation of Massachusetts

Application November 8, 1935, Serial No. 48,845

4 Claims. (Cl. 40—20)

My invention relates to improvements in detachable caps, used in connection with buttons or similar objects, for identifying or ornamental purposes.

5 Referring to the drawing which represents a preferred embodiment of my invention:

Figure 1 is a front view of a strip of material with my improved cap assembled with a button or fastener head and completely concealing the 10 same;

Fig. 2 is an enlarged section taken on the line 2—2 of Fig. 1;

Fig. 3 is an enlarged rear view of my improved cap;

15 Fig. 4 is a side view of my cap shown in Fig. 3; and

Fig. 5 is a section taken on the line 5—5 of Fig. 4.

The purpose of my invention is to provide a 20 cap device which may be secured to buttons or the like objects as a means of identification. My cap device is so formed that it not only serves a useful purpose as an identifying means, but, at the same time, has great ornamental value due 25 to the fact that it presents a novel and attractive appearance when located on the outside of the article.

The particular features of my invention make it especially useful in connection with overshoes 30 or similar articles which have a definite need for an identifying mark. The caps are so constructed that a supply of them carrying different initials may be kept at hand by the store selling the articles with which the caps are to be assembled, and the properly marked cap may be quickly 35 and easily attached to an article at the time it is bought.

Referring in more detail to the embodiment 40 of my invention, as illustrated by the drawing, Fig. 2 shows a strip of material 1 which may be similar to that used in the construction of overshoes. A snap fastener socket 2 of any suitable construction is attached to the strip 1 and the snap fastener cap or button 3 is located on the 45 other side of the strip from the stud receiving part. My improved identifying cap 4 is securely assembled with the snap fastener button 3 and attached, in my preferred form, to conceal completely the cap 3 from view, as shown in Figs. 50 1 and 2. Although I have preferably assembled my identifying cap with a button of a snap fastener socket device, it must be noted that I do not wish to be limited to that particular combination, as my cap could be assembled equally 55 well with a button of a stud means, or a button

which is attached to material for ornamental purposes only. Also, in order to carry out best the purposes of my invention, I have employed a button having a sloping under surface for reasons which will be hereinafter more fully described.

The particular construction of my identifying cap is most clearly set out in Figs. 1—3 which illustrate a device formed of a square, substantially box-like shape, having a base plate 5 and 10 the side walls 6 extending at substantially right angles to the plate. The plate 5 is preferably slightly curved in cross-section so as to follow in some degree a curved contour of the button. An identifying means 7 is pressed into the material 15 of the plate 5, in my preferred form, as represented by the initial H in Figs. 1 and 3. The initial could, of course, be painted or otherwise affixed to the plate or, if the cap is to be used solely as an ornament, the outside surface of the 20 plate and side walls could be attractively embellished.

For the purpose of providing snap fastener action in the identifying cap 4, I have formed the depressed portions providing detents 8 which 25 may be suitably located at various points on the side walls, but which I have preferably located between the corners and directly opposite to each other as shown in Fig. 3. For the correct working of my device, the distance between opposite 30 depressed portions should be less than the greatest diameter of the button. The portions 8 are formed by indenting portions of the material of the side walls adjacent to the free edges inwardly toward the center of the cap as best shown in 35 Figs. 3—5.

In assembling the parts of my installation, the button 3 is first secured to the material 1 in any suitable manner. The free edges of the side walls of the identifying cap are then moved into correct engaging position with relation to the button and the cap is snapped over the button until it completely surrounds the same as shown in Fig. 2. During this snapping movement the depressed portions 8 will engage the edges of the 45 button and, as the cap is pushed downwardly into final position, the side walls of the cap will expand slightly, due to the fact that the distance between the depressed portions is less than the diameter of the button, permitting the depressed 50 portions to be moved over the greatest width of the button into final position substantially opposite the sloping under surface of the button, as shown in Fig. 2. As the depressed portions are moved into final position, the side walls will 55

contract so that the cap is firmly attached to the button. The cap may be disengaged at will by exerting a relatively strong upward pull upon one of the side walls. Unintentional rotation of the cap relative to the button is prevented by the strong friction grip which the fastening means of the cap exerts upon the outside surface of the button.

I have described a square cap which I have found as best serving the objects of my invention, but I do not wish to be limited to that particular formation, because success has been had with caps of other shapes which require only a slightly modified construction from that described in connection with my preferred means. Therefore, although I have illustrated and described a preferred embodiment of my invention, I do not wish to be limited thereby, because the scope of my invention is best set forth in the following 20 claims.

I claim:

1. In combination with a button or the like, a cap for attachment thereto, said cap adapted to enclose the top and sides of said button and comprising a plate portion having a continuous side wall extending therefrom, portions of said side wall being spaced from said button, and said side wall having detents formed therein and located adjacent to the free edge thereof in positions to engage said button when said cap is moved into contact therewith whereby said side wall is expanded in portions and contracted in other portions to permit said cap to be attached to said button by a snap fastener action.
2. In combination with a button or the like, a cap comprising a plate having a continuous yieldable side wall of greater circumference than the greatest circumference of said button and

adapted to cover said button, said side wall having circumferentially disposed button engaging means extending toward each other from said wall and adapted to be engaged beneath a portion of the said button by a combination lateral contraction and expansion action of said wall.

3. In combination with a button or the like having an inwardly sloping under surface, an identification cap comprising a plate having im-perforate side walls extending from said plate and surrounding at least a part of said button, portions of the side walls being spaced from the edges of the button, said side walls being of a size and shape relative to the size and shape of said button to permit lateral yielding movement relative to said button and having a plurality of detents formed therein adjacent the free edges thereof and disposed at substantially diametrical-ly opposite points, said detents adapted to engage the sloping under surface of said button when said cap is moved into contact, and said detents causing lateral movement of the walls during lateral movement of said detents when forced over the edges of said button thereby to secure said cap to said button by a snap fastener action. 25

4. The combination with a substantially round button having a beaded edge of a detachable indica bearing device as described having a sub-stantially flat rectangular top, resilient side walls extending downwardly from said top and having a portion adapted to extend below the beaded edge of said button, said lower side wall portions having inwardly extending shoulders midway of the ends thereof, whereby to permit said side walls to be flexed for removable attachment to 35 said button.

HOWARD J. MURPHY.
